UNITED STATES PATENT OFFICE.

JOHN D. PILTZ, OF DETROIT, MICHIGAN.

AUTOMATIC SAFETY WINDOW AND SCREEN LOCK.

1,389,457.

Specification of Letters Patent. Patented Aug. 30, 1921.

Application filed September 25, 1920. Serial No. 412,687.

To all whom it may concern:

Be it known that I, JOHN D. PILTZ, a citizen of Poland, residing at Detroit, in the county of Wayne and State of Michigan, have invented certain new and useful Improvements in Automatic Safety Window and Screen Locks, of which the following is a specification.

This invention relates to certain new and useful improvements in window locking and screen retaining devices and has particular reference to improved means for locking either sashes of a window in partially open position and improved means for retaining a window screen in place when said sashes are thus locked.

The primary object of the invention is to provide means upon a window screen to penetrate the adjacent rail of a sash and the adjacent window frame member, in combination with means for locking the sash against movement away from the screen whereby removal of the latter is prevented.

With the above general objects in view and others that will become apparent as the nature of the invention is better understood, the same consists in the novel form, combination and arrangement of parts hereinafter more fully described, shown in the accompanying drawings and claimed.

In the drawings, wherein like reference characters indicate corresponding parts throughout the several views,

Figure 1 is a front elevation, partly broken away, of a window frame equipped with the present invention.

Fig. 2 is a vertical sectional view taken upon line II—II of Fig. 1.

Fig. 3 is a transverse sectional view taken upon line III—III of Fig. 2.

Fig. 4 is a horizontal sectional view on an enlarged scale showing the sash locking mechanism in detail as seen when taking a section upon line IV—IV of Fig. 5.

Fig. 5 is a vertical sectional view taken upon line V—V of Fig. 4.

Fig. 6 is a front elevation of the sash locking device, and

Fig. 7 is a perspective view of the casing of the sash locking device.

Referring more in detail to the several views, the present invention contemplates the provision of a rectangular window screen 5 having pins 6 projecting from the top and bottom rails thereof so as to penetrate the bottom rail 7 of the inner window sash 8 and

the sill 9 of the window frame A when said screen is disposed as shown in Figs. 1 and 2, whereby, when the sash 8 is locked in its partially lowered position of Figs. 1 and 2, removal of the screen 5 is prevented from the outside of the dwelling due to the employment of a special form of sash locking device B shown in detail in Figs. 4 to 7 inclusive. The invention also contemplates the provision of a similar locking device B for the outer or upper sash 10 to enable the screen 5 to be used between the top rail 11 of the latter sash and the top member 12 of the window frame when the sash 10 is partially lowered.

As the means for locking the sashes 8 and 10 is identical in construction, detail description of one only of the same is deemed necessary.

As shown in Figs. 3 to 7 inclusive, the window frame is recessed as at 13 so as to enable the casing 14 to be countersunk therein and then secured in place by nails 15 or the like passing through the apertures in the flange 16 of the casing 14 and penetrating the window frame, said flange 16 being provided entirely around the margin of the casing at the open side of the latter. The nails 15 also secure a cover plate 17 on the open side of the casing 14, and this cover plate is provided with suitable sleeves through which project the locking bolts 18 of the sash locking device. Rollers 19 are provided on the bolts 18 so as to insure against resistance to the bolts when entering the transverse grooves 21 provided in the side rail 20 of the sash 8 or 10, which grooves 21 are so disposed that one of the same is positioned to receive the bolts 18 when the sash 8 or 10 is in its proper partially open position to retain the screen 5 against removal. The other groove 21 of each sash is arranged to receive the bolts 18 when their respective sash is in its entirely closed position.

The bolts 18 are rigid with and project from a reciprocable follower 22 arranged within the casing 14 behind the cover plate 17, and this follower is normally outwardly pressed by springs 23 which surround rods 24 and which have one end bearing upon the back wall 25 of the casing 14 and the other end bearing upon the follower 22. Rods 24 are rigidly attached to the back wall 25 and slidably project through the follower 22 to allow movement of the latter and guide the same. The follower 22 is provided with

grooves 26 which slidably receive longitudinal ribs 27 of the casing 14 whereby said follower is additionally guided and supported. A plurality of racks 28 are provided on the follower 22 and each mesh with a freely rotatable spur pinion 29 supported upon a shaft 30 carried by the lower pair of the ribs 27. These racks and pinions insure positive movement of the follower and 10 act in conjunction with the rollers 31 to act as anti-friction means between the follower and the casing 14, said rollers 31 being journaled on the follower 22 in position to bear upon the top wall of the casing 14 as 15 shown in Fig. 5.

A handle 32 is attached to the follower 22 of the mechanism for locking the sash 8, and said handle projects outwardly through the window frame in position to be readily 20 pressed inwardly from within the dwelling so as to release the sash although inaccessible to one outside of the dwelling. A similar handle 32 is provided for the lock mechanism of sash 10 between the sashes 8 and 10 as 25 shown in Fig. 2, and the top rail 33 of the sash 8 is cut away in order to allow said rail to pass the handle 32 when said sash 8 is fully lowered or closed. When sash 8 is 30 fully closed handle 32' may be manipulated from the inside of the dwelling though not from the outside thereof.

It will thus be seen that with the pins 6 penetrating the window frame and the sash as shown in Figs. 1 and 2 and the sash locked 35 in partially open position, the window screen cannot be removed by an unauthorized person from the outside of a dwelling and the invention therefore is in the nature of a safety device.

40 It is believed that the construction and operation as well as the advantages of the present invention will be readily understood and appreciated by those skilled in the art from the foregoing description.

45 Minor changes may be made without departing from the spirit and scope of the invention as claimed.

What is claimed as new is:—

1. A sash locking means including a casing 50 adapted to be countersunk in a window frame, a spring projected follower reciprocable in said casing and having a pair of bolts extending outwardly therefrom, anti-friction rollers journaled upon the free ends 55 of said bolts, a cover plate for the casing having slots through which said bolts slid-

ably project, guiding pins rigidly attached to the back of the casing and slidably extending through said follower, said follower being provided with longitudinal grooves in 60 the upper and lower faces thereof, and longitudinal ribs projecting inwardly from the casing and slidably fitting in said grooves.

2. A sash locking means including a casing 65 adapted to be countersunk in a window frame, a spring projected follower reciprocable in said casing and having a pair of bolts extending outwardly therefrom, anti-friction rollers journaled upon the free ends 70 of said bolts, a cover plate for the casing having slots through which said bolts slidably project, guiding pins rigidly attached to the back of the casing and slidably extending through said follower, said follower being provided with longitudinal grooves 75 in the upper and lower faces thereof, and longitudinal ribs projecting inwardly from the casing and slidably fitting in said grooves, said follower having a plurality of racks 80 formed on its under side, pinions meshing with said racks, and a shaft supported by the lower longitudinal ribs of the casing and upon which said pinions are journaled.

3. A sash locking means including a casing 85 adapted to be countersunk in a window frame, a spring projected follower reciprocable in said casing and having a pair of bolts extending outwardly therefrom, anti-friction rollers journaled upon the free ends 90 of said bolts, a cover plate for the casing having slots through which said bolts slidably project, guiding pins rigidly attached to the back of the casing and slidably extending through said follower, said follower being provided with longitudinal grooves 95 in the upper and lower faces thereof, longitudinal ribs projecting inwardly from the casing and slidably fitting in said grooves, said follower having a plurality of racks 100 formed on its under side, pinions meshing with said racks, a shaft supported by the lower longitudinal ribs of the casing and upon which said pinions are journaled, and anti-friction rollers carried by the follower 105 and engaging the inner surface of the casing.

In testimony whereof I affix my signature.

JOHN D. PILTZ.
